UNITED STATES PATENT OFFICE.

GEORGE HENRY CHARNOCK, OF BUFFALO, NEW YORK.

SILENCER FOR GAS-ENGINE VALVE MECHANISM.

Application filed August 17, 1923. Serial No. 657,971.

To all whom it may concern:

Be it known that I, GEORGE HENRY CHARNOCK, a citizen of the United States, residing at Buffalo, in the county of Erie and 5 State of New York, have invented a new and useful Improvement in Silencers for Gas-Engine Valve Mechanism, of which the following is a specification.

In the type of gas engine valve mechanism now in common use known as an "over-head valve" an undue amount of slack is liable to be present between the outer end of the valve stem and the rocker arm which actuates this stem, which slack in time is 15 likely to produce objectionable noise.

It is the object of this invention to provide a silencer for use between the valve stem and rocker arm which will take up this slack and prevent any noise and which is so 20 constructed that any binding or cramping action is avoided but instead the valve mechanism will be permitted to operate freely, easily and without undue friction or wear on the parts.

25 The present invention is an improvement on the construction for which I filed application for Letters Patent, February 9, 1923, Serial No. 618,145.

In the accompanying drawings: Figure 30 1 is a fragmentary vertical section of an internal combustion engine having its valve mechanism equipped with my invention. Figure 2 is a fragmentary top plan view of the engine embodying my improvements. 35 Figure 3 is a vertical section on an enlarged scale taken on line 3—3, Fig. 2. Figure 4 is a fragmentary vertical section on a reduced scale, taken on line 4—4, Fig. 3. Figure 5 is a detached perspective view of 40 the silencer.

Similar characters of reference indicate corresponding parts throughout the several views.

Inasmuch as this invention is applicable 45 to gas engines of various constructions the showing in the drawings is to be regarded as merely one suitable installation of my invention. As shown, this engine comprises a body or frame 5 containing a cylinder 6, 50 a head 7 at the top of the cylinder, and a piston 8 reciprocating in the cylinder and having its connecting rod 9 coupled with the crank of the driving shaft.

With each cylinder is associated a valve 55 mechanism comprising a fuel inlet valve

and an exhaust valve by means of which live gaseous fuel is admitted to the cylinder and the products of combustion are discharged therefrom, which valves are operated respectively by means comprising rock 60 levers 10, 11. As the mechanism associated with the inlet and exhaust valves is identical in construction, the following description relating to the mechanism for operating the inlet valve 12 will serve to describe the 65 mechanism for operating the exhaust valve.

The inlet valve 12 is adapted to move toward and from a valve seat 13 arranged around the inner end of the fuel inlet or passage 14 in the head of the body. On its 70 upper side this valve is provided with a vertical valve stem 15 which extends to the exterior of the body and is guided in a sleeve 16 mounted in the upper part of the head.

Each of the valves is yieldingly held in its 75 upper closed position by a collar 17 mounted on each valve stem and engaging its upper side with a shoulder formed by a washer 19 interlocking with a groove 20 in the valve stem, and a spring 21 surrounding 80 the valve stem and engaging its lower end with the guide sleeve 16 and its upper end with the underside of said collar.

The inlet and exhaust rock levers are pivotally supported side by side on a shaft 22 85 mounted on the top of the head and the inlet valve rock lever has its rock arm 23 arranged over the upper end of the stem of the inlet valve while its tail 25 is provided with a downwardly opening socket 24 which receives the spherical upper end 26 of an upright push rod 27. In the lower part of the body is rotatably mounted the valve shaft 28 provided with a rotary cam 18 engaging the lower end of a vertical tappet 29. The 90 latter slides in a guide sleeve 30 on the body or frame and transmits lifting movement to the push rod through the medium of a ball 31 interposed between the ball sockets 32, 33, formed on the opposing ends of the 95 tappet and push rod.

The silencer embodying my invention is constructed as follows:

34 represents an inner cross piece of sheet metal or the like provided centrally with an 105 opening 35 which receives the outer part of the valve stem and rests with its opposite ends on the outer side of the collar 17. An outer cross piece of sheet metal or the like is arranged above the inner cross piece and 110

formed so that its central part 36 is deflected inwardly and its opposite ends 37 are deflected outwardly. The outer side of the inwardly deflected part of the outer 5 cross piece engages with the inner side of the rocker arm and the inner side of this part of this cross piece is arranged close to the outer end of the valve stem in the closed position of the valve. The opposite ends 10 of the outer cross piece are provided with openings 40. Upon the opposite ends of the outer cross piece are mounted two guide sleeves 50 which preferably project inwardly from the same and are arranged parallel 15 with and on opposite sides of the valve stem. Each of these guide sleeves may be secured to the outer cross piece in any suitable or approved manner and preferably by providing the same with inner and outer 20 collars or flanges 51, 52 which engage with the inner and outer sides of the respective end of the outer cross piece. Arranged lengthwise on opposite sides of the valve stem are two guide rods 41 which have 25 their inner ends secured to opposite ends of the inner cross piece while their outer parts slide in the guide sleeves 50 of the outer cross piece. The latter is yieldingly held in its elevated position so that the cross pieces 30 are separated by helical springs 42 each of which surrounds one of the guide rods and sleeves and bears at its inner end against the inner cross piece, while its outer end bears against the inner side of the inner 35 collar 51 on the respective guide sleeve. Complete separation of the outer cross piece from the guide rods is prevented when the silencer is removed from the valve mechanism by means of stops 43 arranged on the 40 outer ends of the guide rods and adapted to be engaged by the outer side of the outer cross piece.

In assembling this silencer with the valve mechanism, the same is so adjusted that 45 when the valve is closed by its spring 21 and the rocker arm is in its highest position, the slightest possible clearance is present between the valve stem and the outer cross piece, the parts being held in this relative 50 position by the springs 42 which are under tension. The strength of these springs 42 is, however, less than that of the valve spring 21, so as to ensure closing of the valve whenever the low part of the cam is 55 presented to the tappet.

Whenever the high part of the cam is presented to the tappet, the rocker arm is turned so that the same moves inwardly or downwardly. During the first part of this 60 inward movement of the rocker arm, the outer cross piece is first depressed until it bears against the upper end of the valve stem during which time the tension on the springs 21 is slightly increased. After the 65 outer cross piece bears against the valve

stem, motion is transmitted positively from the rocker arm to the valve stem, whereby the valve is opened in opposition to the spring 21. As the rocker arm moves outwardly, the valve stem moves in unison 70 therewith until the valve has seated, then the rocker arm continues its outward movement independently of the valve to a minute extent, sufficient to ensure tight closing of the valve, during which time the outer cross 75 piece is separated slightly farther from the inner cross piece under the action of the springs 42. These springs at all times cause the motion of the rocker arm to be transmitted to the valve stem gradually and without shock, noise or undue wear, thereby causing the valve mechanism to operate 80 silently and without tapping, thus avoiding the annoyance usually experienced by the operation of valve mechanism as heretofore 85 constructed.

By providing the outer cross piece with the guide sleeves for sliding on the guide rods or pins 41, an extended bearing surface is formed between these parts which 90 permits the same to slide freely on each other and thus avoids undue friction and wear and enables the valve to be operated readily and effectively. In the absence of these sleeves, the pressure of the rocker arm is liable to tip the outer cross piece laterally in one direction or another and produce a cramping, binding and wearing action between the outer cross bar and the guide rods. These guide sleeves are preferably 100 made of brass and the rod of iron which further prevents these parts from sticking on each other and instead permits them to slide freely one relatively to the other and thus ensure smooth operation of the 105 valve mechanism.

I claim as my invention:

1. A silencer for a gas engine valve mechanism having a valve stem, a rocker arm for opening the valve and a spring for closing the valve, comprising two cross pieces one of which is adapted to operate on said spring and the other adapted to operate on said arm, a guide sleeve arranged on one of said cross pieces, a guide pin sliding in said sleeve and connected with the other cross piece, and a spring interposed between said cross pieces. 110

2. A silencer for a gas engine valve mechanism having a valve stem, a rocker arm for opening the valve and a spring for closing the valve, comprising two cross pieces one of which is adapted to operate on said spring and the other adapted to operate on said arm, guide sleeves adapted to be arranged on opposite sides of the valve stem and secured to one of said cross pieces, guide rods adapted to be arranged on opposite sides of said valve stem and sliding in said sleeves and connected with the other 125 130

cross piece, and springs surrounding said guide rods and interposed between said cross pieces.

3. A silencer for a gas engine valve mechanism having a valve stem, a rocker arm for opening the valve and a spring for closing the valve, comprising two cross pieces one of which is straight and adapted to operate on said spring, and the other provided with an inwardly deflected central part adapted to be engaged by said rocker arm and outwardly deflected ends, guide sleeves secured to the ends of one of said cross pieces, guide pins secured to the ends 10 of the other cross piece and sliding in said sleeves, and springs surrounding said guide rods and interposed between said cross pieces.

4. A silencer for a gas engine valve mechanism having a valve stem, a rocker arm for opening the valve and a spring for closing the valve, comprising two cross pieces, one of which is straight and adapted to operate on said spring, and the other provided with 20 an inwardly deflected central part adapted to be engaged by said rocker arm and outwardly deflected ends, guide sleeves secured at their outer ends to the outwardly deflected ends of one of said cross pieces, guide rods sliding in said sleeves and secured at 25 their inner ends to the ends of the other

cross piece, and springs surrounding said rods and interposed between said cross pieces.

5. A silencer for a gas engine valve mechanism having a reciprocating valve stem, a rocker arm arranged across the outer end of said stem and a spring surrounding the stem, comprising inner and outer cross pieces, said inner cross piece being adapted 35 to operate against said spring and provided with a central opening which is adapted to receive said stem, and said outer cross piece having a central inwardly deflected part which is adapted to be arranged between 40 the outer end of said stem and inner side of said rocker arm and also having its ends deflected outwardly and provided with 45 openings, guide sleeves arranged on opposite sides of said inwardly deflected part 50 and each arranged in one of said end openings of the outer cross piece, and provided with inner and outer collars engaging with the inner and outer sides of the outer cross piece, guide rods secured to said inner cross 55 piece and sliding in said guide sleeves and springs surrounding said guide rods and sleeves and each bearing at its opposite ends against the inner cross piece and the inner collar of one of said guide sleeves. 60

In testimony whereof I affix my signature.
GEORGE HENRY CHARNOCK.
